RAM-SHAPED SEAT FOR PLAYGROUND APPARATUS

Robert S. Wormser, Hillsdale, Mich., assignor to Game-Time, Inc., Litchfield, Mich., a corporation of Michigan

Filed Aug. 17, 1966, Ser. No. 3,512

Term of patent 14 years

(Cl. D34—15)

FIG. 1

FIG. 2

FIG. 1 is an elevational view of the left side of ram-shaped seat for playground apparatus showing my new design, the right side being similar thereto,

FIG. 2 is a plan view of the new design,

FIG. 3 is a front, elevational view, and

FIG. 4 is a rear, elevational view of playground apparatus in accord with the design.

The dominant features of my design reside in the portions shown in full lines.

I claim:

The ornamental design for ram-shaped seat for playground apparatus substantially as shown and described.
